[57]**CLAIM**

The ornamental design for a connector for prevention of reverse current, as shown and described.

DESCRIPTION

FIG. 1 is a top plan view of a connector for prevention of reverse current showing my new design;

FIG. 2 is a front elevation view thereof;

FIG. 3 is a rear elevation view thereof;

FIG. 4 is a bottom plan view thereof;

FIG. 5 is a right side elevational view thereof;

FIG. 6 is a left side elevational view thereof; and

FIG. 7 is a cross-sectional view thereof taken along line 7—7 of FIG. 2.
